UNITED STATES PATENT OFFICE.

ANTHONY PERON, OF NEW YORK, N. Y.

COOKING APPARATUS.

Application filed June 24, 1924. Serial No. 721,966.

Some of the important objects of this invention are to provide practical and efficient apparatus for effecting various cooking operations, such as are required to meet the 5 varying demands in restaurant operation.

Special objects also are to make the apparatus attractive for display and advertising purposes; to provide for the removal of objectionable burning or cooking odors, to 10 enable all parts of the device being readily kept clean and sanitary; to provide for cooking by either gas or electricity, or both, and to facilitate the control and the carrying out of the various operations.

15 The foregoing and other objects are attained in this invention by means of certain novel features of construction, combinations and relations of parts as disclosed in the following specification.

20 In the drawings accompanying and forming part of this specification, only one practical embodiment of the invention is illustrated and it is therefore to be understood that the structure may be varied without 25 departure from the broad spirit and scope of the invention as hereinafter defined and claimed.

Figure 1 is a perspective view of the complete installation as viewed from the front.

30 Figure 2 is an enlarged broken detail of the flexible shaft drive and clutch for the broiler.

Figure 3 is a rear elevation of the apparatus.

35 Figure 4 is a horizontal sectional view as on substantially the plane of line 4—4 of Figure 3.

40 Figure 5 is a broken part sectional longitudinal view of the apparatus on an enlarged scale.

Figure 6 is a partly broken view of the control and exhaust flue end of the apparatus.

45 Figure 7 is a vertical sectional view on substantially the plane of line 7—7 of Figure 5, and

Figure 8 is a broken sectional detail of the yielding pan support.

50 As shown in the general view, Figure 1, it will be seen that the apparatus is in the main, a range-like structure provided at the top with a grating 10 beneath which are a series of individually controlled gas burners

11 which can be used for such purposes as are generally carried on on the top of the 55 stove. Below the open flame burners are the oven chambers which are shown provided with the glass front panels 12, 13 for attracting interest to the cooking operations.

One of the special structural features is 60 that the frame of the device is made up of tubular elements which are utilized as flues for promoting the circulation and for carrying off the waste gases and cooking odors. These combined structural and flue elements 65 consist in the illustration of the four tubular corner posts 14 connected in spaced relation at the front and the rear by the tubular side bars 15, 16, all being shown as made of the same size square stock and joined by 70 suitable means such as welding or by coupling sleeves 17 entered at the joints between the legs and the side rails. These parts provide the main strength of the frame, but as many other braces and connecting pieces 75 may be used, as found necessary, such as the several angle pieces designated 18.

The oven chambers are shown in Figures 5 and 7 as defined by the transparent front panel 12, the rear hinged panel or door 19, 80 the bottom plate 20, top plate 21 and end plates 22. The sides of the structure are extended below the bottom of the oven to define a chamber 23 for the burners 24, the ends of this chamber being defined by the 85 end wall 25 and an intermediate wall 26, both extending from front to back of the structure and spaced from the oven end walls 22 to provide upright full width flues 27 extending from the open burner chamber 90 up to a full width flue 28 over the top of the oven and provided by a plate 29 spaced above the oven top.

This construction provides for a circulation of the hot products from the burners 95 across the bottom, up over the ends and across the top of the oven chamber, as indicated particularly by the arrows in Figures 4, 5 and 7. The waste gases are exhausted from the flue space over the oven down 100 through an opening 30 in the top of the rear flue bar 16, which is connected with one end of a header 31 provided with a draught pipe 32 leading to an exhaust fan 33. The down-take 30 is provided in the flue bar substantially mid-length the oven so as to draw the 105

products practically evenly up over both ends of the oven chamber and to prevent the two streams from conflicting.

Two guards 34, 35 are shown extending 5 diagonally from opposite sides of the top passage 28, Figure 4, the first of these serving to deflect the stream rising at the right directly to the down-take and the other operating to turn the uprising stream at the 10 left away from the down-take so that it will be forced to swing around and more nearly coincide with the first flow before passing on to the down-take.

To carry off the cooking odors the front 15 flue bar 15 which extends along the front of the oven is equipped with an outlet or outlets 36 in the bottom of the same and this pipe is connected with the opposite end of the manifold or header 31.

20 The flow of combustion and cooking gases may be controlled by suitable valves or dampers such as the slide shown at 37 governing the passages 36 in the bottom of the oven flue and actuated by a pinion 38 engaging a rack 39 on the edge of the slide, said pinion being carried by a shaft 40 provided with an operating handle 41 located in convenient reach at the back of the oven. During 25 cooking operations this damper may remain closed or only partly open but when the oven is opened, this damper preferably is opened wide to carry off the cooking gases and so prevent a rush of heat and cooking odors into the room.

35 For baking or roasting operations, suitable pans such as indicated at 42 in Figure 7 may be used, but for broiling operations, a special basting pan such as shown at 43 may be employed. This pan is shown as of 40 semi-cylindrical form and seated in the forks or yokes 44 on the upper ends of rods 45 sliding in guides 46 extending up through the bottom of the oven. The lower ends of these rods are shown as resting on rock 45 arms 47 projecting inward from the rock shaft 48 carrying at its end, an arm 49 provided with a roll 50 riding on the periphery of a heart shaped cam 51 from which it will be seen that upon every revolution of the heart cam, the basting pan will be gradually raised and then again gradually lowered. A clutch or other control device may be provided, if desired, for rendering 50 this basting means inoperative when its use is not required. The pan is preferably removable from the supporting yokes 44 and these may be removed from the oven by simply lifting them out of their slide bearings 46.

60 The drive for the heart cam is shown as a sprocket wheel 52 fast on the shaft 53 which carries the cam and engaged by a chain 54 driven by a sprocket pinion 55 on the shaft 56, the latter being shown as operated by flexible shafting 57 detachably

coupled thereto at 58 and extending from a conveniently supported motor 59 which is shown supported on a wall at the back of the apparatus.

The spit 60 is shown as of angular cross 70 section and as removably supported within the oven chamber in line with the drive shaft by means of rollers 61 slipped over the ends of the spit and resting on spaced supporting rolls 62. To hold the spit rollers 75 down on the bearing rolls, forks 63 are shown, each having an arm to extend over and into a groove 64 in the spit collar and having a handle 65 extending out through the rear wall of the oven. These upper 80 holding arms of the forks are shown as sliding in bearings 66 on the same brackets 67 in which the bearing rollers are journaled so that said holding devices will readily slide back and forth for the purpose of holding or releasing the spit.

A clutch connection is shown provided between the drive shaft and spit in the form of a sleeve 68 journaled in a bearing 69 in the end wall of the oven and having a squared or angular bore to slidably fit over the squared or angular end portion 70 of the drive shaft and the squared or angular end of the spit, said sleeve being shiftable from the position shown in Figure 2, where it is housed in its bearing inwardly into engagement over the end of the spit, or vice versa, by a shifting fork 71 having a relatively rotatable engagement with a collar 72 on the outer end of the clutch sleeve.

This construction makes it possible to readily couple or uncouple the spit with respect to the drive shaft.

For the broiling operations an electric heater is usually employed, the same being shown as consisting of a series of heating coils 73 supported beneath a reflector 74 in the top of the oven chamber and controlled, preferably in sections, by a suitable switch or switches 75 located conveniently on the 105 end of the oven structure.

By the proper control of the heating coils, the broiling operation may be carried on at the proper rate and when the basting mechanism is employed, the pan will be automatically lifted to baste the fowls or other food on the spit, once to every predetermined number of revolutions of the spit. Usually it is sufficient to baste the products about once to every fifteen turns 115 and the sprocket gearing is shown as proportioned to effect approximately this result.

The upper burners 11 are shown as individually controlled by valves 76 connected with a header 77, and similarly, the lower burners are controllable by individual valves 78 connected with a lower header 79. In addition to the selective control, the oven burners are shown as controllable as a unit 125 130

by means of master valves 80 located near the opposite ends of the header 79 so that variable degrees of heat may be applied to different portions of the ovens and then if desired, such heat may be either decreased or diminished in the different parts of the oven, all at once. To equalize the gas supply, the headers may be joined together at opposite ends by piping 81 and the supply 10 piping 82 may be brought in at one of such ends.

To catch any overflow or splash from pots and pans over the upper burners, relatively shallow water pans 83 are shown supported 15 immediately below the upper burners and removable through a way 84 in the rear wall of the apparatus.

A finish is provided about the top of the apparatus by upwardly extended end walls 20 85 connected by a wall 86 shown as rearwardly offset at 87 to enable it to catch any overflow such as might be occasioned by boiling operations on the top of the apparatus.

25 The electric heater may be used alone or in conjunction with the gas burners, but when not in use and the gas burners are in service, the coils are preferably covered to prevent accumulation of grease or moisture 30 thereon by a relatively close-fitting cover plate 88 sliding in guides beneath the coils and withdrawable through a slot in the back of the oven as indicated in Figure 7.

A window 89 may also be provided in the 35 door or rear wall of the oven chamber for observing cooking operations, and thermometers 90, Fig. 7, or other indicating instruments may be provided for indicating oven temperature or other conditions.

40 The invention, it will be seen, makes it possible to carry out all of the various cooking operations required in restaurant service and the device is readily controlled to secure just the results desired. The structure is 45 strong, simple and compact, easily kept clean and sanitary and is attractive for display purposes. Furthermore, the cooking operations can be carried on without objectionable odors or release of heat from the 50 oven.

To prevent injury to the basting mechanism in the event of the basting pan being lifted into engagement with the material on the spit, the supporting rods are shown 55 as of yielding telescopic construction, Figure 8 with expansion springs 91 inside the tubular telescopically related parts, 45, 45^a, the lower sections 45 being in the form of sleeves closed at their lower ends to remain 60 resting on the rocker arms 47 when the upper sections 45^a are lifted out of the same, the springs being pinned to these upper sections at 92 so that they too will be lifted out when the basting mechanism is removed 65 from the oven.

The springs are properly tensioned so as to support the usual amount of liquid at the level to properly cooperate with the material on the spit but adapted to yield at a relatively slight additional pressure so 70 that the pan will automatically yield immediately it comes in contact with an extra large fowl or other matter on the spit.

To conserve the heat, the end walls 25 and top wall 29 defining the flue passages 75 at the ends and over the top of the oven chamber are preferably lined with asbestos or other thermal insulating material, as indicated at 93. This lining on the top wall prevents absorption of too much of the heat 80 by the water pans 83 supported on this top wall.

As the spit is supported at its opposite ends on rollers, it turns easily and smoothly and is held against accidental dislodgement 85 by the overhanging arms of the hooks or forks 63. The spit is readily removable at any time, however, after the clutch sleeve 68 is withdrawn as in Figure 5, by simply pushing in the hooks 63 to carry the overhanging portions thereof clear of the bearing rolls 61 on the ends of the spit.

90 What is claimed is:

1. Cooking apparatus comprising a supporting frame including longitudinally extending tubular bars at the front and the rear of the structure, a manifold at one end of the structure in communication with the ends of said tubular frame bars, an exhaust flue connected with said manifold, an oven chamber open into one of the tubular frame bars and a heat conducting flue extending over the top of the oven chamber and open to the other tubular frame bar. 95

2. Cooking apparatus comprising a supporting frame including longitudinally extending tubular bars at the front and the rear of the structure, a manifold at one end of the structure in communication with the ends of said tubular frame bars, an exhaust flue connected with said manifold, an oven chamber open into one of the tubular frame bars, a heat conducting flue extending over the top of the oven chamber and open to the other tubular frame bar and a damper controlling the opening into one of the frame 100 bars. 110

3. Cooking apparatus comprising corner posts connected by tubular side bars to form part of a supporting frame work, an oven 115 supported by said frame work, a combustion chamber and oven heating flues supported by the frame work, one of the tubular frame members having an exhaust opening leading into the oven chamber and another of the tubular frame members having an opening to one of the oven flues and an exhaust conduit connected with the tubular frame members. 120

4. Cooking apparatus comprising a frame 125

- including substantially rectangular hollow corner posts connected by similar hollow frame bars provided one with an opening in the top of the same and the other with an opening in the bottom of the same, an oven chamber in communication with said bottom opening, an oven flue in communication with the top opening and damper mechanism controlling one of said openings.
10. Cooking apparatus having a frame work including hollow corner posts connected by hollow frame bars, an external manifold connecting the hollow frame bars, an exhaust conduit extending from the manifold, an oven chamber open to one of the hollow frame bars and an oven flue open to the other frame bar.
11. Cooking apparatus having a frame work including hollow corner posts connected by hollow frame bars, an external manifold connecting the hollow frame bars, an exhaust conduit extending from the manifold, an oven chamber open to one of the hollow frame bars, an oven flue open to the other frame bar and exhaust mechanism connected with the exhaust flue.
12. In cooking apparatus, an oven chamber, hollow flue bars in the upper portion of the same, electric heater units in the space between said hollow flue bars, one of said flue bars being open to the oven chamber for exhausting the oven gases, an external burner for heating the oven and a slide operable between the flue bars to shut off the electrical heater units from the interior of the oven.
13. In cooking apparatus, a rotating spit, a basting pan, and means for conjointly turning the spit and automatically raising and lowering the basting pan toward and away from said spit.
14. In cooking apparatus, a rotary spit, a cam shaft, speed reduction gearing from the rotating spit to the cam shaft, a basting pan and cam means driven by the cam shaft for alternately raising and lowering the basting pan.
15. In cooking apparatus, an oven, a spit removably journaled in said oven, a basting pan removably supported in the oven and means for rotating the spit and for automatically raising and lowering the basting pan.
16. In cooking apparatus, the combination with a rotatable spit and a basting pan, of means for effecting relative motion of said basting pan and rotatable spit toward and away from each other and a yielding connection interposed in such means for preventing injury to the parts in the event of contact between the basting pan and material on the spit.
17. In cooking apparatus, a rotatable spit and a basting pan, means for alternately raising and lowering the basting pan toward and away from the spit and yieldable connections in such means for preventing injury to the parts in the event of contact between the pan and material on the spit.
18. In combination with a rotatable spit, a basting pan, yieldable supports for said pan and raising and lowering mechanism engaged with said yieldable supports.
19. In combination with a rotatable spit and a basting pan, yieldable supporting means for one of such parts and means for effecting relative motion of such parts toward and away from each other.
20. In cooking apparatus, an oven chamber, a heat flue extending over the top of said oven chamber, rectangular tubular frame members in the upper corners of the

oven chamber, one open to the heat flue and the other open directly to the oven chamber and an exhaust manifold at one end of the apparatus, open to the ends of both said

5 tubular frame members.

21. In cooking apparatus, tubular corner posts, tubular front and rear frame members connected with said posts and having extensions through two of the corner posts, 10 exhaust connections engaged with such extensions, an oven chamber open to one of the tubular frame members and a heat flue open to the other tubular frame member.

22. In cooking apparatus, tubular corner 15 posts, tubular front and rear frame members connected with said posts and having extensions through two of the corner posts, exhaust connections engaged with such extensions, an oven chamber open to one of

the tubular frame members, a heat flue open 20 to the other tubular frame member and damper mechanism for controlling entry into one of said tubular frame members.

23. Cooking apparatus comprising in combination a stove structure having a supporting shelf in the upper portion of the same, a shallow water pan slidably and removably supported on said shelf, burners directly over said water pan, an utensil supporting grating above said burners and constituting 25 the top of the stove structure and an upstanding apron about the edges of said grating for returning overflow from cooking utensils to the water pan.

In witness whereof, I have hereunto set 30 my hand this 6th day of June, 1924.

ANTHONY PERON.
